UNITED STATES PATENT OFFICE.

NELSON S. HOPKINS, OF FORT WAYNE, INDIANA, ASSIGNOR TO GENERAL ELECTRIC COMPANY, A CORPORATION OF NEW YORK.

CONDENSER.

No. 873,751.

Specification of Letters Patent.

Patented Dec. 17, 1907.

Application filed November 15, 1902, Serial No. 131,476.

To all whom it may concern:

Be it known that I, NELSON S. HOPKINS, a citizen of the United States, residing at Fort Wayne, county of Allen, State of Indiana, have invented certain new and useful Improvements in Condensers, of which the following is a specification.

It has been found in the manufacture and operation of condensers that the greatest stress tending to break down a condenser is at the edges or corners of the sheets or strips forming the conducting portion of the condenser.

The object of my invention is the construction of a condenser which is so made that this liability to break down at the edges is reduced to a minimum. I have accomplished this by so arranging the conducting strips of the condenser that the parallel edges 20 of adjacent strips or sheets of conducting material are separated by a distance which is appreciably greater than the thickness of the dielectric which separates the bodies of the sheets.

For a better understanding of my invention, reference may be had to the accompanying drawing in which

Figure 1 is a perspective view showing the construction of one form of condenser embodying my invention; Fig. 2 is a plan-view showing the same form; and Fig. 3 shows another form of condenser embodying my invention.

Referring to the construction shown in Fig. 1 the sheets *a* there shown are made of some conducting material such as tin foil and are joined together in any suitable manner to form one of the conducting members of the condenser. The sheets *a* may be each 35 provided with integral extensions *t* at one corner which form the terminals of the respective sheets. The other conducting member of the condenser is formed of a series of sheets *b* which are similar to the sheets *a*, 40 and are provided with extensions *t'* similar to the extensions *t* of sheets *a*. The sheets *b* are turned however so that the extensions *t'* are diagonally opposed to the extensions *t* of the plates *a*. Sheets *c* formed of any suitable dielectric material separate the conducting sheets *a* and *b*.

As is clearly shown in the drawing, sheets *a* and *b* are laterally displaced with respect to one another so that while the similar edges

are parallel, the terminal corners of adjacent sheets are separated by a distance greater than the length of the diagonal of one of the sheets. As a result of this construction parallel edges of adjacent sheets are separated by a considerable lateral distance, and the liability of the condenser to break down between these edges is accordingly decreased. The sheets of the dielectric *c* may be somewhat larger than the sheets *a* and *b*, if desired. For instance they may be made of a shape similar to that of the sheets *a* and *b* but of such size that a diagonal is equal to or greater than the distance between the terminal corners of the sheets *a* and *b*. While I have shown sheets *a* and *b* as being rectangular in shape, it will of course be readily understood that other shapes could be used in condensers possessing the advantages of my construction.

In the construction shown in Fig. 3, *a'* and *b'* represent the strips of conducting material provided with terminal extensions *t''* *t'''*. The strips *a'* and *b'* are separated from each other by layers or sheets of dielectric *c'*. The sheets *a'*, *b'* and *c'* are rolled together 80 to form a roll condenser. The strips *a'* and *b'* are displaced laterally however so that the parallel edges of adjacent strips are separated by a distance considerably greater than the thickness of the dielectric strips *c'* as is clearly 85 shown in the drawing. With this construction if the ends of the conducting strips *a'* and *b'* are separated somewhat more than the thickness of the dielectric strips *c'*, the edges of the conducting strips will be separated 90 in all places by a distance greater than the thickness of the dielectric separating the body of the strips.

What I claim as new, and desire to secure by Letters Patent of the United States, is,— 95

1. A condenser composed of sheets or strips of some conducting material arranged with edges parallel and separated by interposed strips of dielectric, the adjacent sheets or strips of conducting material being so placed that the distance between similar edges is greater than the distance between the bodies of said sheets or strips.

2. A condenser composed of sheets or strips of some conducting material arranged with edges parallel and separated by interposed strips of dielectric, adjacent sheets or strips of conducting material being so placed

that the distance between parallel edges is greater than the distance between the bodies of said sheets or strips.

3. A condenser composed of sheets or strips of some conducting material separated by interposed sheets or strips of dielectric, the sheets or strips of conducting material being so placed that similar edges are a uniform distance apart and so that no considerable extent of the edges of adjacent strips are as close together as the distance between the bodies of said sheets or strips.

4. A condenser composed of two or more sheets or strips of good conducting material arranged with edges substantially parallel and separated by strips of dielectric, adjacent sheets or strips of conducting material being bodily displaced laterally with respect to each other.

5. A condenser comprising active strips or sheets of conductive material arranged with edges parallel, interposed dielectric material, adjacent strips or sheets of different polarities being displaced laterally with respect to each other so that no considerable extent of the edges of adjacent strips are as close together as are the bodies of said strips.

6. A condenser comprising substantially rectangular active conductive plates of opposite polarities and interposed dielectric material, said plates being diagonally displaced with reference to each other.

In witness whereof I have hereunto set my hand this fifth day of November, 1902.

NELSON S. HOPKINS.
